SECTION LINED PUMP SHELL FOR
DREDGING

Millard F. Crawford, Jackson, La.

Application June 4, 1943, Serial No. 489,678

3 Claims. (Cl. 103—114)

This invention relates to pumps and more particularly to a section lined pump shell for dredging pumps.

An object of the invention is to provide a complete liner for the inside of centrifugal pumps adapted to resist abrasive wear caused by the pumped material.

A further object is to provide a liner of this type which can be easily and quickly changed at small cost without welding which ordinarily causes the shell to warp.

A further object is to provide apparatus of this character which will be formed of a few strong, simple and durable parts, which will be inexpensive to manufacture, and which will not easily get out of order.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawings forming a part of this specification:

Figure 1 is a cross sectional view, with portions in elevation, of a centrifugal pump equipped with a sectional liner constructed in accordance with the invention.

Figure 2 is a longitudinal sectional view taken on the line 2—2 of Figure 1 with parts in elevation.

Figure 3 is a detail view partly in elevation and partly in section showing the keystone sector of the liner.

Referring now to the drawings in which like characters of reference designate similar parts in the various views, 10 designates the pump shell which is provided with supporting flanges 11 whereby the pump may be anchored to a suitable foundation. The pump impeller 12, which rotates within the shell, is carried by a driven shaft 13. The face plates 14 of the shell are bolted to flanges 15 on the shell, the shaft 13 being passed through a stuffing box 16 in one of the face plates. An intake pipe 17 is provided with a flange 18 which is bolted to a flange 19 on the other face plate as shown at 20. An outlet pipe 21 is formed integral with the shell at a tangent thereto, see Figure 2. Water pipes 22 enter the first named face plate. These pump parts are conventional.

In centrifugal pumps of this type, as the pump material moves outwardly within the shell the

hydraulic pressure reaches a maximum at the inner peripheral wall of the shell. It is in this portion of the shell that the abrasion is maximum and the primary object of the invention is to minimize the effects of the abrasion as well as to make it possible to remove the parts subjected to this abrasion as will now be described.

An annular lining 23, of abrasive resistant material is mounted on the inner peripheral wall of the shell and comprises a plurality of sectors 24 of U-shape in cross section, the side walls 25 of the sectors being thinner than the bottom portion 26 of the sectors, see Figure 1. The increased thickness of the bottom portion 26 is adapted to resist the maximum abrasion which occurs at the inner periphery of the shell 10 where hydraulic pressure and velocity are greatest.

The sectors are assembled in the shell as follows; beginning at the outlet pipe 21 the initial sector marked by the legend initial, and which is provided with an extension 27, is first inserted with the extension serving as a liner for the exhaust pipe. The second sector inserted also serves as a liner for the exhaust pipe and is marked by the legend second. The third, fourth, fifth and sixth sectors next laid in sequence are laid on the bottom of the pump shell and are marked with corresponding legends. Next the seventh to the sixteenth sectors are laid in sequence beginning on the opposite side of the initial sector from the second sector and are marked with corresponding legends. This leaves a wedge shaped space between the sixth and the seventeenth sectors for the reception of the keystone sector which is marked with a corresponding legend.

The keystone sector, see Figure 3, is provided with a long shank 28 which extends radially through a nipple 29 in the shell 10. The keystone sector is tapered on both sides to fit between the sixth and seventeenth sectors and tighten all of the sectors when a wedge 30 is driven through a slot 31 in the shank against a pair of metal washers 32 which are disposed on the shank and have a gasket 33 disposed between them on the shank and a second disk gasket 34 disposed between them and the nipple to prevent leakage from the shell.

In further carrying out the invention face plate liners 35 of suitable wear resisting material, are disposed inwardly of the face plates to receive rubbing contact of the impeller, see Figure 1. These liners are secured in place by cap screws 36 and adjusting screws 37 the latter

carrying lock nuts 38. The adjusting screws are threaded through face plates and the cap screws are engaged through the adjusting screws and threaded into the liners. By slackening off all of the cap screws 36, and loosening the lock nuts 38, on the adjusting screws 37, the latter may be screwed in or out to adjust the face plate liners to any desired position. After the adjustment is made the lock nuts 38 and cap screws 36 are retightened to preserve the adjustment.

The object of adjusting the face plate liners is to keep them very close to the impeller to prevent the water pressure from dropping. If the water pressure is not maintained the abrasive material will work in between the impeller and the liners and wear out both rapidly. With this type of adjustment it is easy to keep the face plate liners very close to the impellers on either side all the way round even though the impeller is not in perfect line with the shell.

The material from which the liners of the shell and the face plates is constructed varies in accordance with the material being pumped. For example, if acid material is being pumped the liners may be formed of acid resisting material such as rubber. When gravel and like abrasive material is being pumped the liners may be formed of abrasive resisting metal such as manganese steel. The sectors of the shell liner may be molded to shape so that no machine work is necessary.

The sectors of the lining at the top of the shell, designated by the legends twelfth and thirteenth, are provided with coacting grooves of semicircular cross section as shown at 35 which coact in forming a vent opening which communicates with a vent opening 36 in the shell.

From the above description it is thought that the construction and operation of the invention

will be fully understood without further explanation.

What is claimed is:

1. The combination with the U-shaped peripheral wall of a centrifugal pump shell, of U-shaped sectors having their legs relatively thinner than the bottoms of the sectors, said sectors being received against the inner peripheral wall of the shell, a tapered key sector between two of the first named sectors serving to wedge and maintain all the sectors in assembled position within the shell, all of said sectors being formed of abrasive resisting material, a shank on the keystone sector engaged through an opening in the shell to project exteriorly of the shell, there being a slot in the shank outside of the shell, a wedge driven through said slot, a pair of metal washers between the shell and the wedge, a gasket disposed between the metal washers, and a gasket disposed between one of the metal washers and the shell.
2. The combination with the shell of a centrifugal pump, a curved lining for the shell, said lining having an inner curvature and formed of sectors, one of said sectors being in the form of a tapered keystone serving to wedge and maintain the remaining sectors in assembled position within the shell, and means for securing the keystone sector to the shell.
3. The structure as of claim 2 and in which the means for securing the keystone sector to the shell comprises a long shank on the sector engaged radially through the shell and having a slot formed therein outside of the shell, a wedge in said slot, a pair of metal washers disposed on the shank underneath the wedge, a gasket disposed between the washers, and a second gasket disposed between the washers and the shell.
